United States Patent Office

Des. 228,815
Patented Oct. 23, 1973

228,815

SURGICAL LANCET

Stephen P. Campbell, Jr., Brookline, Mass., assignor to
Damon Corporation, Needham Heights, Mass.

Filed Oct. 22, 1971, Ser. No. 191,964

Term of patent 14 years

Int. Cl. D24—02
U.S. Cl. D83—1 J

FIG. 1

FIG. 2

FIG. 3

FIG. 4

FIG. 1 is a perspective view of a surgical lancet embodying my design and showing the top, back, and one side thereof;

FIG. 2 is a perspective view showing the front, top and other side of the lancet of FIG. 1;

FIG. 3 is a top plan view of the lancet of FIG. 1; and
FIG. 4 is a bottom plan view of the lancet of FIG. 1.

I claim:

The ornamental design for a surgical lancet, as shown.
